13551

JAN 30, 1883

UNITED STATES PATENT OFFICE.

JOHN L. POPE, OF CLEVELAND, OHIO.

DESIGN FOR A HARNESS-BIT.

SPECIFICATION forming part of Design No. 13,551, dated January 30, 1883.

Application filed November 11, 1882. Term of patent 14 years.

To all whom it may concern:

Be it known that I, JOHN L. POPE, of Cleveland, in the county of Cuyahoga and State of Ohio, have invented and produced a new and original Design for Harness-Bits, of which the following is a specification, reference being had to the accompanying photograph, forming a part thereof.

My invention relates to a novel design for the loops and cheek-pieces of harness-bits; and it consists in certain features of configuration and ornamentation, which will be hereinafter more particularly described and claimed.

In the accompanying photographs, Figure 1 shows a view of a "half-cheek" bit, and Fig. 2 a view of a "full-cheek" bit, both of which have my design applied.

Like letters of reference in the two views designate like parts.

20 A is the bit proper, and B B the loops or rein-rings. The cheek-pieces are made fancy and are cast integral with the loops. For convenience of description, I shall assume these cheek-pieces to be made of two parts, C and D. 25 The part C is the smaller of the two and adjoins the loop. From its solid neck portion extend two curved bars, c c, and one intermediate Y-shaped or bifurcated bar, e, the effect of which arrangement is the formation of three 30 openings, plain on visual inspection. The part D is composed essentially of two substantially semicircular bars, a a, and two other substantially semicircular bars, o o, the latter small in size and located within the space formed by 35 the bars a a, and running into the latter where

they join the part C. The ring-like figures formed by the bars a a and o o have the appearance of being arranged eccentrically to each other. The outer portion of the inner ring-like figure is connected by two short pieces 40 to the exterior figure, which at this point (about on a line with its center) is drawn out, as it were, forming a triangularly-shaped opening small in size. At the extremity of the cheek-piece is a little curved projection, not really 45 essential to my novel design, and between the bars o o there is also an ornamental piece running longitudinally of the figures.

My invention may be used in either a snaffle-bit or bar-bit and in a full-cheek or a half-cheek bit.

What I therefore claim as new, and desire to secure by Design Letters Patent, is—

1. A harness-bit provided with cheek-pieces of substantially the configuration and design 55 shown.

2. The cheek-pieces of a harness-bit, composed of two parts, C and D, of substantially the contour shown and described.

3. The cheek-pieces of a harness-bit, composed of two parts, C and D, presenting openings between the bars substantially like those shown and described.

In witness whereof I have hereunto set my hand this 3d day of November, 1882.

JOHN L. POPE.

In presence of—

WALTER A. BIDDLE,
GEORGE F. EBERHARD.
